UNITED STATES PATENT OFFICE

2,568,260

MACHINE FOR WRAPPING COVERINGS
AROUND ARTICLES

Paul Spagnoli, San Francisco, Calif.

Application November 30, 1948, Serial No. 62,706

10 Claims. (Cl. 270—27)

1

The present invention relates to improvements in a machine for wrapping a covering around an article. It consists of the combinations, constructions, and arrangement of parts, as herein-after described and claimed.

In my United States Letters Patent No. 2,385,477, granted September 25, 1944, I disclose a mattress wrapping machine that will take a flat mattress, compress and roll the mattress into a cylindrical form while wrapping paper there-around. Uniform wrapping pressure is applied to the mattress by this patented machine throughout the entire wrapping operation, and the rolled mattress occupies far less storage space than a flat mattress.

An object of the present invention is to provide a machine for tightly wrapping covering about an article. Although this machine may be utilized in conjunction with the patented machine for rolling and wrapping a mattress, I do not wish to be confined to this particular use. The present machine is adapted for wrapping various articles, such as mattresses, box springs, pieces of furniture, etc., with the wrapping material or covering drawn tightly around the wrapped article.

Other objects and advantages will appear as the specification continues. The novel features will be set forth in the claims hereunto appended.

For a better understanding of the invention, reference should be had to the accompanying drawings, forming part of this application, in which:

Figure 1 is a side elevation of my machine for wrapping a covering around an article;

Figure 2 is an isometric view illustrating a pair of U-shaped bars engaging opposing faces of a mattress, the bars being supported by a driving head forming part of my machine;

Figure 3 is an isometric view of a clamp that I employ for holding the U-shaped bars in engagement with the interposed mattress;

Figure 4 is an enlarged transverse sectional view taken along the line IV—IV of Figure 1, illustrating the start of the wrapping operation;

Figure 5 is a view similar to Figure 4, but showing the mattress completely wrapped and still supported by the U-shaped bars;

Figure 6 is a view similar to Figure 5, but discloses the wrapped mattress withdrawn from the U-shaped bars;

Figure 7 discloses a plurality of articles after they have been wrapped with my machine in a protective covering;

Figure 8 is an end elevation of a slightly modi-

2

fied form of my present machine, portions being broken away, and illustrating it in conjunction with my patented mattress-wrapping machine above mentioned;

Figure 9 is a transverse sectional view showing the driving head and article-supporting bars employed in the modified form of machine and illustrating the start of a mattress-wrapping operation; and

Figure 10 is a horizontal transverse sectional view taken along the line X—X of Figure 9.

While I have shown only the preferred forms of my invention, it should be understood that various changes, or modifications, may be made within the scope of the claims hereunto annexed without departing from the spirit thereof.

In carrying my invention into practice, I provide a base A having a main frame B secured thereto and rising therefrom. This main frame 20 includes spaced-apart upright channels 10 and 11 which are interconnected by horizontally-disposed angle irons 12 and platforms 12'. Braces 14 (see Figure 8) extend between the base A and the channels 10 and 11 to reinforce the main frame B. An overhead beam 15 is secured to the channels 10 and 11 so as to project horizontally therefrom (see Figure 1). The free end of this beam is supported by braces 16, which are anchored to a ceiling 17, beam, or the like. Also, I provide the rods 18a anchored to the channel 10 for supporting the free end of this beam.

The channel 11 has a driven shaft 18 journaled therein, which is aligned with a driving shaft 19. A conventional clutch 20 is adapted for connecting or disconnecting these shafts together, and is actuated by a throw-lever 21. Any suitable means may be employed for driving the shaft 19. For this purpose I have shown a sprocket 22 that is connected by a chain 23 to a sprocket 24 on a speed-reduction unit 25. The latter is operated by a motor 26.

The driven shaft 18 has a rotatable head C secured thereto so as to turn therewith. Figure 1 discloses a brake 21a that is designed to apply a braking action on the rotative head C whenever the throw lever 21 is moved to the left to disengage the clutch. The lever 21 occupies the position shown in Figure 1 when the clutch is engaged. This head carries a rigid U-shaped lower bar D1 and a swingable U-shaped upper bar D2. These bars project from the head in parallel relation with the axis of rotation 18a of the head (axis of shaft 18). Bar D1 is adapted to support an article E from the underside of the latter, while the bar D2 is made to overlie

the article to clamp the article upon the lower bar D1. The rotatable head C is disposed on one end of the article E, and the bars D1 and D2 are sufficiently long to have their closed ends d¹ and d², respectively, extend to the opposite end of the article (see Figure 1).

Referring to Figures 1, 2, 4 and 5, it will be noted that the U-shaped bar D1 has arms 27 provided with reduced ends 27a, the latter being insertable through any one of a plurality of openings 28 formed in the rotatable head C. Nuts 27b (see Figure 1) secure these reduced ends to the head.

In Figures 1 and 2, I show the arms 29 of the U-shaped bar D2 as being hinged by bolts 30 to clevises 31. The latter have stub shafts 31a (see Figure 1) that are adapted to extend through openings 32, provided in the head C. Nuts 31b anchor the stub shafts 31a in adjusted position on the head.

It will be obvious from the foregoing structure that the U-shaped bars D1 and D2 may be adjusted toward and away from the axis of rotation 18a. The adjustment of these bars will depend upon the thickness of the interposed article E.

The bar D2 may be swung into raised position, as suggested by its dot-dash line illustration in Figure 1, and its closed end d² engaged with a catch 33 carried by the overhead beam 15. When the bar D2 is thus raised, the article E may be moved endwise into place over the lower bar D1 so as to be supported thereby. Subsequently, the bar D2 may be swung downwardly on its hinge bolts 30 for overlying and clamping the article E in place.

An inverted bell-crank member indicated generally at F is pivoted at 34 to the free end of the overhead beam 15 (see Figure 1). This member includes a vertically-disposed support 35, which is moveable toward and away from the closed ends d¹ and d² of the bar D1 and D2, respectively, when the member F is swung on its pivot (see Figure 1). The support 35 carries a bolt-like shaft 36, which is moveable into alignment with the axis 18a of the rotatable head C.

Referring to Figures 1 and 3, it will be noted that I provide a clamp 37 that is supported on the shaft 36. This clamp is secured to a driven sprocket 38 on the shaft 36. The clamp 37 is provided with an extension 37a that underlies and supports the closed end d¹ of the bar D1; and, also, with a hook 37b that is engageable over the closed end d² of the upper bar D2. The bars D1 and D2 parallel one another; and, also, parallel the axis of rotation 18a about which the article E rotates during the wrapping operation. It will be noted that the extension 37a is longer than the hook 37b. This permits the extension 37a to be guided into a position underneath the closed end d¹ of the lower bar D1 so as to support the latter. Thereafter, the support 35 is moved closer to the mattress E, and the closed end d² of the upper bar D2 is depressed slightly and the hook 37b is engaged over the closed end d².

Rotary motion may be imparted to the clamp 37 by the sprocket 38 in synchrony with rotation of the head C. For this purpose, the driven shaft 18 is connected through a sprocket-chain connection 41 so as to drive a pinion 42 meshing with a gear 43 on a horizontal shaft 44 disposed under the beam 15. This shaft carries a pinion 45 at its forward end that drives a gear 46 rotatably carried by the support 35. The gear 46 operates a sprocket 47, which is connected by a

chain 48 to the sprocket 38 previously mentioned. The gear 46, sprocket 47, chain 48, sprocket 38 and clamp 37 swing with the bell-crank member F.

In order to operate the clutch 20 from the forward end of the machine (left side of Figure 1), I provide a clutch-control lever 49 that is pivotally mounted at 50 to a standard 51 rising from the overhead beam 15 (see Figure 1). This control lever is connected by a link 52 to the upper end of the throw-lever 21, the latter operating the clutch 20.

The bell-crank member F has its horizontal arm 53 attached by an eyelet 54 to one end of a cable 55. The opposite end of this cable is attached to a counterweight 56, the intermediate portion of the cable being trained over a pulley 57. The purpose of the counterweight is to assist in moving the bell-crank member F. The latter 20 can be swung until the support 35 is substantially horizontal.

As previously expressed, I do not desire to be limited to any particular article to be wrapped. In Figures 1, 2, 4 and 5 I show the article E as comprising a mattress, which may be of any size. This mattress is clamped between the lower bar D1 and the upper bar D2 by the clamp 37 at the start of the wrapping operation. Rotation of the head C and the sprocket 38 in unison will rotate the mattress around the axis of rotation 18a. It is during this rotation of the mattress that the wrapping is accomplished.

Figures 1 and 4 disclose wrapping paper G having its free end 58 clamped between the upper bar D2 and the upper surface of the mattress or other article E. Upon turning the head C in the direction of the arrow 59, paper will be drawn from a roll (not shown) and wrapped tightly around the article. Figure 5 discloses sections 60 of the paper as passing beneath the arms 27 of the bar D1 and sections 61 of the paper extending over the arms 29 of the upper bar D2. After a desired number of layers of paper have been wrapped around the article E, the paper is cut and its cut end 62 is pasted by glue 63 against the adjacent underlying portion of the paper in which the article has been wrapped.

Thereafter, the clamp 37 is disengaged from the closed ends d¹ and d² of the bars D1 and D2, respectively, the support 35 is retracted as suggested by the dot-dash lines of the support in Figure 1. Next, the article E is pulled to the left in Figure 1, thus withdrawing the article and its wrapping or covering from the bars. The sides 64 of the paper G extend beyond the ends of the mattress and may be folded to enclose the mattress.

Figure 7 illustrates a mattress E1 and box springs E3 that have been wrapped together in the paper G by using my machine. It will be understood that other articles may be wrapped in the manner set forth.

Referring to Figures 9 and 10, I disclose a slightly modified form of the rotatable head, which has been designated at C1. This head has the lower bar D1 adjustably secured thereto in the same manner as shown in Figure 1. However, the head C1 has a radial slot 65 which takes the place of the openings 32 in Figures 4 and 5.

The bar D3 is swingably secured by a bolt 66 to a clevis 67 (see Figure 10). The latter has a stub shaft 68 thereon, which projects through the radial slot 65. This clevis is anchored in adjusted position on the head C1 by a clamping nut 69. In this modification, the lower U-shaped bar

D1 and the clamp 37 remain the same as in the first embodiment.

Figure 8 discloses a mattress-compressing and wrapping machine, which is designated generally at H. This machine has been illustrated in my United States Letters Patent No. 2,385,477, granted September 25, 1944. It is shown in Figure 8 of the present drawings as being used in conjunction with the second embodiment of the current invention, although it could operate with the first embodiment.

The mattress-compressing and wrapping machine H includes a roll-about frame 70 on which a mattress-supporting platform 71 is fulcrumed at 72. The front end of this platform is yieldingly supported by springs 73 that bear against the frame 70 and the platform 71 with sufficient force for normally holding the rear end of the platform down upon a member 74 carried by the frame. Tension springs 75 are connected to the frame 70 and platform 71 to urge the latter toward its normal position.

The platform 71 has been illustrated as being introduced into a position underneath the bars D1 and D3. It will be understood that the head C1 in Figure 8 is rotated by the same mechanism as shown in Figure 1. One end of a mattress E2 has been clamped between the bars D1 and D3 and the head C1 rotated so as to partially roll this mattress into spiral shape with the mattress tightly compressed. The front end of the platform yields during the rolling of the mattress.

In order to feed wrapping paper to the mattress E2 during the rolling operation, I provide a roll of paper J, which is carried by a notched support 76. The paper 77 is fed from the roll J and overlies the platform 71. The paper passes under a guide 78 and over a paper cutter 79. Figure 9 shows the free end 77a of this paper as being clamped between the underneath surface of the mattress E2 and the arms 27 of the lower U-shaped bar D1. The cutter 79 is spaced the desired distance from the mattress-rolling head C1 so that one or more extra layers of paper can be wrapped around the mattress after it has been completely rolled.

The paper is stretched over the platform 71 and the mattress E2 is placed on the top of this paper. The end of mattress nearest the head C1 is placed between the bars D1 and D3; also, the free end 77a of the paper is placed over the arms 27. Thereafter, the swingable platform F is lowered and the clamp 37 is engaged with the bars D1 and D3 in the same manner as previously described.

When the mattress E2 and paper 77 are clamped in position, the head C1 is rotated in the direction of the arrow 80. During the rolling of the mattress, the front end of the platform 71 is urged downwardly by the rolling up of the mattress against the tension of the springs 73 and 75. This will make a tight roll. The paper 77 is wrapped during the rolling process so as to lie between adjacent layers of the mattress roll. The front end of the platform 71 swings downwardly during the rolling of the mattress.

After the mattress is completely rolled, it may be rotated through additional turns to wrap paper around the roll. Thereupon, a knife (not shown) may be passed along a slot 79a in the paper cutter 79 for cutting the paper. The cut end of the papers is glued to the outer wrapping of the roll. The pressure exerted by the spring-pressed platform 71 is sufficient to cause the glue

to secure the cut end of the paper to the adjacent layer of paper.

It should be noted that in both forms of the present invention, the head C or C1 and the clamp 37 are rotated in unison, thus preventing any twisting of the article-engaging bars.

I claim:

1. In a machine for wrapping a covering around an article; a main frame having a head rotatably mounted thereon; a plurality of spaced-apart lower bars carried by the head and projecting laterally therefrom to support an article from the underside of the latter; at least one upper bar also carried by the head to overlie the article and arranged to clamp the article to the lower bars; the bars paralleling the axis of rotation of the head and revolving the article for a wrapping operation when the head is rotated; the bars projecting at least to the end of the article opposite the rotatable head; the bars embracing and sustaining the article along its entire length; a support carried by the frame and being moveable toward and away from the said end of the article and having a shaft thereon moveable into alignment with the axis of rotation of the head; this shaft being supported in its operative position in alignment with said axis by said support and frame; a clamp on the shaft securable to the bars at said end of the article to hold the bars in parallel relation with one another after the article has been clamped between the bars; and means for rotating the head to revolve the article; the support and clamps being moveable into an out-of-the-way position to allow endwise withdrawal of the article when the clamp is disengaged from the bars.

2. In a machine for wrapping a covering around an article; a main frame having a head rotatably mounted thereon; a plurality of spaced-apart lower bars carried by the head and projecting laterally therefrom to support an article from the underside of the latter; at least one upper bar also carried by the head to overlie the article and arranged to clamp the article to the lower bars; the bars paralleling the axis of rotation of the head and revolving the article for a wrapping operation when the head is rotated; the bars projecting at least to the end of the article opposite the rotatable head; the bars embracing and sustaining the article along its entire length; a support carried by the frame and being moveable toward and away from said end of the article and having a shaft thereon moveable into alignment with the axis of rotation of the head; this shaft being supported in its operative position in alignment with said axis by said support and frame; a clamp on the shaft securable to the bars at said end of the article to hold the bars in parallel relation with one another after the article has been clamped between the bars; and driving means for rotating the clamp to turn the bars at said end of the article about the axis of rotation in synchrony with rotation of the head, the support and clamps being moveable into an out-of-the-way position to allow endwise withdrawal of the article when the clamp is disengaged from the bars.

3. In a machine for wrapping a covering around an article; a main frame having a head rotatably mounted thereon; a plurality of spaced-apart bars carried by the head and projecting laterally therefrom in parallel relation with the axis of rotation of the head; the bars being made for clamping upon an article to support the latter and revolve the article for a wrapping operation when

the head is rotated; the bars projecting at least to the end of the article opposite the rotating head; the bars embracing and sustaining the article along its entire length; the frame including a beam; a support swingably secured to the beam and being moveable toward and away from said end of the article and having a shaft thereon moveable into alignment with the axis of rotation of the head; a clamp on the shaft securable to the bars at said end of the article to hold the bars in parallel relation with one another after the article has been clamped between the bars; and means for rotating the head; the support and clamps being moveable into an out-of-the-way position to allow endwise withdrawal of the article when the clamp is disengaged from the bars.

4. In a machine for wrapping a covering around an article; a main frame having a head rotatably mounted thereon; upper and lower bars carried by the head and projecting laterally therefrom in parallel relation with the axis of rotation of the head; the bars being made for clamping upon an article to support the latter and revolve the article for a wrapping operation when the head is rotated; the bars projecting at least to the end of the article opposite the rotating head; the bars embracing and sustaining the article along its entire length; the frame including a beam; a support swingably secured to the beam and being moveable toward and away from the said end of the article and having a shaft thereon moveable into alignment with the axis of rotation of the head; a clamp on the shaft securable to the bars at said end of the article to hold the bars in parallel relation with one another after the article has been clamped between the bars; means for rotating the head; and driving means for rotating the clamp to turn the bars at said end of the article about the axis of rotation in synchrony with rotation of the head; the support and clamps being moveable into an out-of-the-way position to allow endwise withdrawal of the article when the clamp is disengaged from the bars.

5. In a machine for wrapping a covering around an article; a main frame having a head rotatably mounted thereon; upper and lower bars carried by the head and projecting laterally therefrom in parallel relation with the axis of rotation of the head; the bars being made for clamping upon an article to support the latter and revolve the article for a wrapping operation when the head is rotated; the bars projecting at least to the end of the article opposite the rotating head; the bars embracing and sustaining the article along its entire length; the frame including a beam; a support swingably secured to the beam and being moveable toward and away from the said end of the article and having a shaft thereon moveable into alignment with the axis of rotation of the head; a clamp on the shaft securable to the bars at said end of the article to hold the bars in parallel relation with one another after the article has been clamped between the bars; means for rotating the head; and driving means for rotating the clamp to turn the bars at said end of the article about the axis of rotation in synchrony with rotation of the head; the support and clamp being moveable into an out-of-the-way position to allow endwise withdrawal of the article when the clamp is disengaged from the bars; said driving means including means automatically disengageable to discontinue driving of the clamp when the support is swung away from said end of the article.

6. In a machine for wrapping a covering around an article; a main frame having a head rotatably mounted thereon; a plurality of spaced-apart lower bars carried by the head and projecting laterally therefrom to support an article from the underside of the latter; at least one upper bar also carried by the head to overlie the article and arranged to clamp the article to the lower bars; the bars paralleling the axis of rotation of the head and revolving the article for a wrapping operation when the head is rotated; the bars projecting at least to the end of the article opposite the rotatable head; the bars embracing and sustaining the article along its entire length; a support carried by the frame and being moveable toward and away from the said end of the article and having a shaft thereon moveable into alignment with the axis of rotation of the head; this shaft being supported in its operative position in alignment with said axis by said support and frame; a clamp on the shaft securable to the bars at said end of the article to hold the bars in parallel relation with one another after the article has been clamped between the bars; means for rotating the head to revolve the article; the upper and lower bars being disposed equidistantly on opposite sides of said axis of rotation; and means connected to the head for adjusting both the upper and lower bars relative to one another to vary the space therebetween, while maintaining the upper and lower bars equidistantly on opposite sides of said axis of rotation.

7. In a machine for wrapping a covering around an article; a main frame having a head rotatably mounted thereon; a pair of U-shaped parallel bars arranged in spaced relation with one another to receive an article therebetween; each bar having spaced-apart arms embracing and sustaining the article along its entire length; the ends of the bars being secured to the head; the arms of the bars paralleling the axis of rotation of the head; a support carried by the frame and being moveable toward and away from the closed ends of the bars; a clamp rotatably mounted on the support and being securable to the closed ends of the bars to hold the bars in engagement with the article; the clamp, when in operative engagement with the bars, being disposed for rotation about an axis coinciding with the axis of rotation of the head; and means for rotating the head and clamp in synchrony about the axis of rotation of the head.

8. In a machine for wrapping a covering around an article; a main frame having a head rotatably mounted thereon; upper and lower U-shaped bars arranged in spaced relation with one another to receive an article therebetween; each bar having spaced-apart arms embracing and sustaining the article along its entire length; the ends of the bars being secured to the head; the arms of the bars paralleling the axis of rotation of the head; a support carried by the frame and being moveable toward and away from the closed ends of the bars; a clamp mounted on the support and being engageable with the closed ends of the bars to hold the bars in clamping relation with the article; the clamp, when in operative engagement with the bars, being disposed for rotation about an axis coinciding with the axis of rotation of the head; and means for rotating the head and the clamp in synchrony about the axis of rotation of the head; the support and clamp being moveable into an out-of-the-way position to clear the closed ends of the bars and thus allow

the article to be withdrawn from between the bars at the closed ends thereof.

9. In a machine for wrapping a covering around an article; a rotatably-mounted head; upper and lower U-shaped bars arranged in spaced parallel relation with one another to receive an article therebetween; each bar having spaced-apart arms embracing and sustaining the article along its entire length; the ends of the bars being secured to the head; the upper bar having hinges therein arranged for swinging of that bar toward and away from the lower bar; the arms of the bar paralleling the axis of rotation of the head, with the bars disposed on opposite sides of said axis; a support moveable toward and away from the closed ends of the bars; a clamp rotatably carried by the support for turning around said axis when the support is moved into a position adjacent to the closed ends of the bars; the clamp having an extension thereon moveable under the closed end of the lower bar to support that end, and a hook engageable over the closed end of the upper bar to retain that bar down against the article; the extension being longer than the hook, whereby the extension will provide a support for the lower bar while the hook is being engaged with or disengaged from the upper bar.

10. In a machine for wrapping a covering around an article; a rotatably-mounted head; upper and lower U-shaped bars arranged in

20

25

30

spaced parallel relation with one another to receive an article therebetween; each bar having spaced-apart arms embracing and sustaining the article along its entire length; the ends of the bars being secured to the head; the upper bar having hinges therein arranged for swinging of that bar toward and away from the lower bar; the arms of the bar paralleling the axis of rotation of the head, with the bars disposed on opposite sides of said axis; a support moveable toward and away from the closed ends of the bars; a clamp rotatably carried by the support for turning around said axis when the support is moved into a position adjacent to the closed ends of the bars; the clamp having an extension thereon moveable under the closed end of the lower bar to support that end, and a hook engageable over the closed end of the upper bar to retain that bar down against the article.
